UNITED STATES PATENT OFFICE.

JOHN E. HUNT, OF FREMONT, OHIO.

AUTOMATIC RAILWAY SIGNALING DEVICE.

Specification of Letters Patent.

Patented July 2, 1912.

1,031,119.

Application filed March 12, 1910. Serial No. 548,779.

To all whom it may concern:

Be it known that I, JOHN E. HUNT, a citizen of the United States, residing at Fremont, in the county of Sandusky and State 5 of Ohio, have invented certain new and useful Improvements in Automatic Railway Signaling Devices, of which the following is a specification.

It is now well known that notwithstanding 10 the utility accorded to the "block system" on railways; it frequently occurs that the engineer fails to observe the block because of either inattention, or the condition of the weather, as in case of a violent storm 15 rendering it quite impossible to see the semaphore, or the light shown thereby; and the general purpose and object of my invention is to furnish additional means by way of torpedo signaling, which is operated in unison with the semaphore.

Referring to the drawings herewith, Figure 1 represents in perspective a general view of my device; shown in connection with a semaphore and post therefor; the 25 housing being omitted. Fig. 2 represents a section on the line A A of Fig. 1; the housing which was omitted in Fig. 1, being herein shown. Fig. 3 represents a top plan of Fig. 2, the cover and housing being 30 omitted, and the torpedo with its carrier being thrown into normal. Fig. 4 represents a detail opposite the view seen in Fig. 1. Fig. 5 represents a partial detail of the carrier.

35 Coming now to a more detailed description of my device: In Fig. 1 is shown a signal post 1 upon which is mounted a semaphore 2 which is operated in the usual manner familiar to railway men. In this particular instance, the semaphore is supposed 40 to be operated either from the station, or by throwing of a switch. Ordinarily the semaphore is made to turn about a pivot bolt, but for the purpose of operating my device, 45 I make said bolt 3 to turn with the semaphore, the bolt head being made fast to the semaphore by suitable means 4. Said bolt is made to pass through the post, and turns therein, and in order that my device may 50 operate in unison with said semaphore I make said bolt, oppositely, to carry a sprocket wheel 5, see Fig. 4, which is secured thereto as any mechanic would suggest.

55 In the drawings, Fig. 1, the semaphore is shown at danger signal, and accordingly, as

will now be explained, the torpedo 6 is shown in place upon the rail.

As represented in Figs. 1 and 2 my device is placed at right angles with the track, and conveniently near the same. A bed piece 60 7 is made to carry the operative parts, and to which a housing 8 may be made fast. Mounted upon said bed is a cover 9 which is removably secured thereto by bolts 9^a; and within said cover is a slidable bar 10 which 65 I call a torpedo carrier, made to carry an oscillating shaft 11, which in turn carries a dog 12, made to operate in a slot 12^x cut or formed therein. Said dog is provided with a notch or slot 12^a, and when raised to 70 operative position, it is the office thereof to receive and hold a suitable looped wire, or other suitably formed substitute therefor, 13, which is secured to and projects from the torpedo 6, and serves as a handle by which 75 it is carried. Said cover is provided with a magazine 14 of sufficient capacity to hold a reasonable number of torpedoes; and the handle is of such length, that, allowing for the necessary action of said carrier when the 80 torpedo is central under the magazine, and the carrier is in normal position, as in Fig. 3, the handle is engaged by said notch or slot. By reason of which, so long as said dog is held in operative position, said 85 torpedo is made to go and come with the operation of said carrier. Said bed piece is provided with a slot 15 which registers with said dog and permits the same to fall therein, when the carrier is in operated position, 90 and said dog is released. Normally said dog is in operative position; and it is held therein by virtue of an overweighted trip 16, which is pivoted to said carrier by a pivot bolt 16^a, and which trip has its heavy 95 end resting upon the projecting end of said shaft 11, and made to engage a stud 17 which rises from said shaft.

Manifestly when the engine or a car runs over the torpedo the handle becomes worthless and distorted in shape, and therefore, in order that it may be released, and not be drawn back into the device, after the torpedo has been exploded, I make the light 100 end of said trip 18, to reach forward to a point near the rail, and within the path of the tread of the car wheel, by means of which, as the torpedo is exploded by a passing train or engine, the trip is operated and 105 the shaft 11 is made free to turn, and in con- 110

sequence, the dog which is carried thereby, is set free and made to rotate about the axis of said shaft 11, which it does by virtue of its own weight; and thus as said torpedo 5 is exploded, said dog is made to rotate and become disengaged from said handle. Said dog being thus disengaged, the free end thereof comes to rest with its back against the end of said slot 15, as may be understood 10 from the dotted outline in Fig. 2, where the dog is represented in rotated position; and, by reason of this arrangement, as the carrier is returned to normal, the dog is rotated back to normal, and rides with its back upon the bed piece, while the heavy end of the 15 trip falls in front of the stud 17.

It may now be understood that normally one of the torpedoes is at rest upon the bed piece, as seen in Fig. 3, with the outer end of the 20 looped handle engaged with the notch 12^a, and with the torpedo central under the magazine. While in this position, the column of torpedoes rests thereon; being surmounted by a load 19 which serves to feed 25 the torpedoes as required. In order that said torpedoes may be thus fed, and to accommodate the handle thereof, I provide said magazine with a communicating slot 20, which registers with a like slot 21, formed 30 in said cover.

For operative purposes the handle 13 is preferably made flush with the upper end of the torpedo, as shown in the drawings; though the handle may be made to surmount 35 the same. In the latter case it must be understood that the handle must be made to extend sufficiently beyond the center line, so that when a torpedo is central under the magazine, the easy operation of the device 40 will not be interfered with: in short so that the adjacent torpedo will then ride freely upon the upper side of the handle. The mechanic will now observe that in either case the thickness of the carrier is to be accordingly; so that the upper side of the handle 45 shall be of uniform height with the upper side of said carrier: and thus facilitate the easy going and coming of the carrier under the column of torpedoes. And to this end I 50 provide said carrier with a slotted recess 22, see Fig. 5, which accommodates said handle; its depth being slightly greater than the thickness of said handle, so as not to draw the mutilated handle as the carrier is being 55 returned to normal; the column of torpedoes, during this operation, being made to rest upon the full thickness of said carrier outside of said recess, and to ride thereon.

Referring to Figs. 2 and 3, it may be noticed that during such return to normal a fresh torpedo is made to fall, as soon as the support of the carrier is withdrawn therefrom; and that this occurs before said carrier is fully returned. But this is a matter 60 of no importance, the fact being governed

by the required action of the carrier, due to the distance between the center of the magazine and the rail. It may now be observed that said magazine is so located that when a fresh torpedo is made to fall, it will fall 70 clear of the mutilated handle of the previously exploded torpedo; and this is intentionally so, since the chamber 23 within which the carrier operates, requires to have a reasonably close fit; and in consequence, if the fresh torpedo was to fall upon said handle, it would project above the limits of the chamber and block the operation of the device. I have just said that the chamber requires "a reasonably close fit": in connection therewith it may now be explained that 75 this is particularly so, between the limits of the notch 12^a when the carrier is in normal position, and the limit of forward travel of the carrier; the purpose being both to prevent loss of the torpedo, and to be able to hold the torpedo at such a level after it leaves the housing, that it will be safely landed in its appointed position, on top of the rail.

In order that my device may be operated in unison with the semaphore, and a torpedo be placed in its appointed position, as the semaphore is raised to danger signal, I make said sprocket wheel 5 to bear a chain 90 24; to the several ends of which I connect a cable or other suitable means 25 which interveningly is made to pass about pulleys 26 and 27, and which at the other end is connected with said carrier by means 28 and 29. 30 represents the usual lever, which is pivoted upon the post by bolt 31, and has its ends connected with cables 32, which in the usual manner are made to pass about a pulley 33, and, it may be understood, are 95 operated either at the station, or by the throwing of a switch. Intervening said ends, the usual rod 34 is connected with the semaphore. It may now be understood that in order to give said carrier its required action, 100 said sprocket wheel is given diameter accordingly, due regard being had for the action of the semaphore. Aside from the means already described, where circumstances permit, the required action of said 105 carrier may be obtained by connecting said cables 25 over a pulley 35 and to the end of said lever 30 as shown in dotted outline.

36 is a stop or lug, which limits the operation of the carrier in one direction.

37 represents a suitable rod or other means which cooperates with a bracket 38 to limit the fall of the load 19; and 39 is a flanged collar or hub for securing the sprocket wheel 5 to the bolt 3.

It may now be observed that the operation of my device may be accomplished otherwise than by the throwing of a switch, or by direct operation of the semaphore from the station; since it may be made to operate 125 130

whenever the semaphore is operated, whether electrically or otherwise; and hence I broadly claim means.

Having now fully described my invention
5 what I claim is:

1. In a device of the character described, the combination of a slotted bed piece; a 25
slidable torpedo carrier mounted and guided thereon, and which comprises: a slidable, slotted and recessed bar; an oscillatable pawl-controllable dog; and an overweighted trip, the heavy end of which operates as a 30
pawl for the control of said dog—said dog and trip, both being pivotally carried by said bar, with said trip near its advancing end, and said slot in said bed piece being made to register with the slot in said bar, 35
when said carrier is in operated position, thereby and then permitting the release of said dog by the operation of said trip; guiding means for said carrier, and mechanical means for the operation thereof; substantially as set forth.
- 10 15 20
2. In a device of the character described, pivotally carried by said bar, with said trip near its advancing end, and said dog operating, when held, to engage the handle of said torpedo; said slot in said bed piece being made to register with the slot in said bar, when said carrier is in operated position, thereby and then permitting the release of said dog by the operation of said trip; substantially as set forth.

the combination of a slotted bed piece; a 25
slidable torpedo carrier mounted and guided thereon, and which comprises: a slidable, slotted and recessed bar; an oscillatable pawl-controllable dog; and an overweighted trip, the heavy end of which operates as a 30
pawl for the control of said dog—said dog and trip, both being pivotally carried by said bar, with said trip near its advancing end, and said slot in said bed piece being made to register with the slot in said bar, 35
when said carrier is in operated position, thereby and then permitting the release of said dog by the operation of said trip; guiding means for said carrier, and mechanical means for the operation thereof; substantially as set forth.

In testimony whereof I affix my signature
in presence of two witnesses.

JOHN E. HUNT.
